(57) **ABSTRACT**

The programmable CMOS-based nonlinear function synthesizer is a circuit that assumes that the required nonlinear function can be approximated by the summation of hyperbolic tangent ($\tan h$) functions with different arguments. Each term of the $\tan h$ function expansion is realized using a current-controlled current-conveyor (CCCCII), or an operational transconductance amplifier (OTA)) with a different bias current. The output weighted currents of these CCCCCIIs or OTAs are algebraically added to produce the output current. The present circuit can be easily integrated, extended to include higher order terms of the $\tan h$ -function expansion and programmed to generate arbitrary hard nonlinear functions. By controlling the bias current and without changing the aspect ratios of the transistors, various $\tan h$ functions with different arguments from the same topology can be obtained.

PROGRAMMABLE CMOS-BASED NONLINEAR FUNCTION SYNTHESIZER

BACKGROUND OF THE INVENTION

1. Field of the Invention

The present invention relates generally to synthesizers, and particularly to a programmable CMOS-based nonlinear function synthesizer that allows for the nonlinear function to be approximated by summation of hyperbolic tangent ($\tan h$) functions via different arguments.

2. Description of the Related Art

Despite its limited accuracy, it is very well known that analog nonlinear signal processing is much faster than its digital counterpart. This justifies the use of analog nonlinear signal processing in applications where speed, not the accuracy, is the major concern. Such applications cover a wide range including, but not limited to, medical equipment, instrumentation, analog neural networks and telecommunications. Therefore, over the years, several approaches have been reported for synthesizing analog nonlinear functions. These approaches suffer from at least the following disadvantages. Firstly, only one or two functions can be realized, and secondly, the designer must use piecewise linear approximations to approximate the required nonlinear function.

Thus, a programmable CMOS-based nonlinear function synthesizer solving the aforementioned problems is desired.

SUMMARY OF THE INVENTION

The programmable CMOS-based nonlinear function synthesizer is a circuit that assumes that the required nonlinear function can be approximated by the summation of hyperbolic tangent ($\tan h$) functions with different arguments. Each term of the $\tan h$ function expansion is realized using a current-controlled current-conveyor (CCCCII), or an operational transconductance amplifier (OTA) with a different bias current. The output weighted currents of these CCCCCIIs or OTAs are algebraically added to produce the output current.

The present circuit can be easily integrated, extended to include higher order terms of the $\tan h$ -function expansion and programmed to generate arbitrary hard nonlinear functions. By controlling the bias current and without changing the aspect ratios of the transistors, various $\tan h$ functions with different arguments from the same topology can be obtained.

These and other features of the present invention will become readily apparent upon further review of the following specification and drawings.

BRIEF DESCRIPTION OF THE DRAWINGS

FIG. 1 is a schematic diagram of the class AB CCCCCII used in the programmable CMOS based nonlinear function synthesizer, according to the present invention.

FIG. 2 is a block diagram of the programmable CMOS based nonlinear function synthesizer using the CCCCCIIs of FIG. 1, according to the present invention.

FIG. 3 is a plot showing simulated and calculated results of the $\tan h(x)$ function with RRMS error=9.35% according to the present invention.

FIG. 4 is a plot showing simulated and calculated results of the $\tan h(2x)$ function with RRMS error=4.76% according to the present invention.

FIG. 5 is a plot showing simulated and calculated results of the $\tan h(3x)$ function with RRMS error=6.4% according to the present invention.

FIG. 6 is a plot showing simulated and calculated results for a multi-weighted nonlinear function according to the present invention.

FIG. 7 is a plot showing simulated and calculated results for a second multi-weighted nonlinear function according to the present invention.

FIG. 8 is a plot showing simulated and calculated results for a third multi-weighted nonlinear function according to the present invention.

Similar reference characters denote corresponding features consistently throughout the attached drawings.

DETAILED DESCRIPTION OF THE PREFERRED EMBODIMENTS

The programmable CMOS-based nonlinear function synthesizer 200 (shown in FIG. 2) is a circuit that approximates a required nonlinear function by the summation of hyperbolic tangent ($\tan h$) functions with different arguments. Each term 15 of the $\tan h$ function expansion is realized using a current-controlled current-conveyor (CCCCII) 100 (or an operational transconductance amplifier (OTA)) with a different bias current. The output weighted currents of these CCCCCIIs (OTAs) are algebraically added. The programmable CMOS-based 20 nonlinear function synthesizer 200 can be easily integrated, extended to include higher order terms of the $\tan h$ -function expansion and programmed to generate arbitrary hard nonlinear functions. By controlling the bias current and without changing the aspect ratios of the transistors, various $\tan h$ 25 functions with different arguments from the same topology can be obtained.

The key idea of the present programmable nonlinear function synthesizer 200 is the fact that many hard nonlinear functions can be approximated by the summation of $\tan h$ 30 functions as shown in equation (1).

$$y(x) = \sum_{n=1}^N \gamma_n \tanh(\alpha_n x). \quad (1)$$

In equation (1), the current $y(x)$ represents the required 35 nonlinear function, x represents the normalized input voltage, α_n is a positive integer or non-integer constant and γ_n is a positive or negative integer or non-integer weighting factor.

Usually the current-controlled current-conveyor (CCCCII) or the operational transconductance amplifier (OTA) is treated as a linear building block to design active filters, oscillators and amplifiers. However, the relationship between 40 the input voltage V_y of a CMOS current-conveyor and the current I_x is a saturated nonlinear function. This nonlinearity is partially attributed to the nonlinear performance of the translinear loop and the current-mirrors used in designing the current conveyor. The present programmable CMOS-based 45 nonlinear function synthesizer uses the inherent nonlinearity of the CCCCCII 100 (shown individually in FIG. 1, and as a cascade in FIG. 2) to approximate the function $\tan h(\alpha_n x)$ where α_n is an integer or non-integer number. A multiple of the $\tan h(\alpha_n x)$ functions with different values of α_n are then 50 weighted by arbitrary current-gain amplifiers (202a, 202b, 202c, and 202d) with gain= γ_n to finally add them together and produce the output current $y(x)$ of equation (1). The inherent 55 nonlinearity of the OTA can be used for the same purpose.

The present CCCCCII is a simple class AB translinear circuit 60 formed of transistors M1-M13, as shown in FIG. 1. The current-voltage transfer characteristic of the class AB CCC- 65 CII shown in FIG. 1 is a saturated nonlinear function. The

transfer function is represented by a hyperbolic tangent ($\tan h$) function. By controlling the bias current of FIG. 1, and without changing the aspect ratios of the transistors, it is possible to obtain several $\tan h$ functions with different arguments. For example, $\tan h(x)$, $\tan h(2x)$ and $\tan h(3x)$ may be obtained from the same topology.

The output current of each CCCII can be weighted using current amplifiers or current mirrors as shown by transistors M14-M21 of FIG. 1. The aspect ratios of transistors M14-M21 are selected based on the required value of γ_n . Equation (1) can be realized by adding the weighted output currents of a number of CCCCII with different biasing currents and weighting factors γ_n .

FIG. 2 shows a possible realization of equation (1) with $n=4$. A bias voltage $V_B = \sqrt{I_B/k}$, where I_B is the biasing current of the CCCCII, x is a normalized input voltage $= V_m/V_B$, and k is the transconductance factor.

PSPICE simulation software and 0.35 μm process parameter technology was used to investigate the accuracy of approximating the transfer characteristic of a class AB CCCCII by a $\tan h$ function and the accuracy of the present analog function synthesizer. The DC supply voltages used are $\pm 1.2\text{V}$ with biasing currents $I_{B1}=60\text{ }\mu\text{A}$, $I_{B2}=250\text{ }\mu\text{A}$ and $I_{B3}=500\text{ }\mu\text{A}$ for the functions $\tan h(x)$, $\tan h(2x)$ and $\tan h(3x)$ respectively. The current-gain amplifiers, formed of transistors M14-M21 of FIG. 1, can provide three arbitrary gains that can be obtained by adjusting the aspect ratios (W/L) of these transistors. The aspect ratios of the transistors M1-M13 of all the CCCCIIIs were 50 $\mu\text{m}/3\text{ }\mu\text{m}$. The simulation results obtained are shown in FIGS. 3-8 together with the calculations obtained using MATLAB. The accuracy of the simulation results is measured using the Relative Root Mean Square (RRMS) error criterion expressed by equation (2).

$$RRMS = \sqrt{\frac{\sum_{m=1}^M \left(\frac{y_{simm} - y_{calm}}{y_{calm}} \right)^2}{M}} \quad (2)$$

In equation (2) y_{simm} is the value obtained from simulation at point m, y_{calm} is the value obtained from MATLAB calculations and M is the total number of points used in calculation. The results obtained are shown in plots 300, 400, and 500 of FIGS. 3-5 and RRMS errors obtained are 9.35%, 4.76% and 6.4% for the functions $\tan h(x)$, $\tan h(2x)$ and $\tan h(3x)$ respectively. Using these three $\tan h$ functions, the following three nonlinear functions were simulated.

$$I_{out} = 632(-0.6 \tan h(x) + 0.8 \tan h(2x) + 0.2 \tan h(3x)) \quad (3)$$

and

$$I_{out} = 632(0.6 \tan h(x) - 0.2 \tan h(2x) - 0.2 \tan h(3x)) \quad (4)$$

and,

$$I_{out} = 632(-0.6 \tan h(x) + 0.3 \tan h(2x) + 0.2 \tan h(3x)) \quad (5)$$

In equations (3)-(5) the factor 632 is just a scaling factor. The results obtained are shown in plots 600, 700, and 800 of FIGS. 6-8, together with the calculations obtained using MATLAB. For the functions of equations (3) and (4) the errors obtained were in the range $x=\pm 2.5$ are 9.76% and 19.5 8% for the function of equation (3) and (4) respectively. For the function of equation (5) the error obtained was in the

range $x=\pm 1.2$ is 3.73%. The results were obtained without any attempt to optimize the circuit to minimize the errors. The proposed approach can be easily expanded to accommodate extremely hard nonlinearities if needed. The major advantage of the present topology is the current-controlled programmability which, contrary to other available realizations, allows many hard nonlinear functions to be synthesized from the same topology, just by controlling a number of bias currents of the CCCCII (or OTA) blocks and/or the gains of current amplifiers.

During implementation, care must be taken with aspect ratios of the transistors used and the possible errors due to transistor mismatches and the channel length modulation effects. Fortunately, because of the built-in programmability, these errors can be corrected by fine tuning of the bias currents of each CCCCII (or OTA) and/or the gains of the current amplifiers until the synthesized function closely fits the required nonlinear function.

It is to be understood that the present invention is not limited to the embodiments described above, but encompasses any and all embodiments within the scope of the following claims.

We claim:

1. A programmable CMOS-based nonlinear function synthesizer, comprising:

a CMOS circuit having a plurality of bias inputs, a plurality of current outputs and a corresponding plurality of signal inputs, an n-th one of the current outputs in relation to its corresponding signal input defining a saturated nonlinear transfer function characterized by the relation,

$$\tan h(\alpha_n x),$$

where α_n is a positive integer/non-integer constant, and x represents a normalized voltage as the signal input;

weighing circuitry comprised of current mirrors operable with each output of the plurality of current outputs to form a weighted output for each said output; summation circuitry connected to the weighted outputs, and providing an algebraic sum of the weighted outputs, the algebraic sum being characterized by the relation,

$$y(x) = \sum_{n=1}^N \gamma_n \tanh(\alpha_n x),$$

where current y(x) represents the required nonlinear function, and γ_n is a positive/negative integer/non-integer weighting factor for each value of n, where n is an integer between 1 and N, where N represents a total number of the current outputs;

and programmable bias currents I_{Bn} connected to the bias inputs, where α_n is a positive integer/non-integer constant that can be programmed by the bias inputs.

2. The programmable CMOS-based nonlinear function synthesizer according to claim 1, wherein the CMOS circuit comprises a plurality of current-controlled current-conveyors (CCCCIIIs).

3. The programmable CMOS-based nonlinear function synthesizer according to claim 1, wherein the CMOS circuit comprises a plurality of operational transconductance amplifiers (OTAs).

4. The programmable CMOS-based nonlinear function synthesizer according to claim 1, further comprising unique values for each bias input of the plurality of bias inputs, wherein correspondingly unique hyperbolic tangent functions are obtained.

5. The programmable CMOS-based nonlinear function synthesizer according to claim 1, further comprising fixed transistor aspect ratios of the weighing circuitry based on the γ_n weighing factors, the fixed transistor aspect ratios not affecting the programmability of the programmable CMOS- 5 based nonlinear function synthesizer.

6. The programmable CMOS-based nonlinear function synthesizer according to claim 5, wherein the fixed transistor aspect ratios (W/L) are approximately 50 $\mu\text{m}/3 \mu\text{m}$.

7. A programmable CMOS-based nonlinear function syn- 10 thesizer, comprising:

a plurality of second generation current controlled current conveyors (CCCCIIs) each CCCCCII of the plurality having a first input terminal, a second input terminal, a bias terminal accepting a programmable bias current I_{B_n} and an output terminal, the plurality arranged in a circuit in which all of the second input terminals are connected together to a common reference potential, and all of the first input terminals are connected together accepting a signal input, each CCCCCII operating in a region defining a saturated nonlinear transfer function characterized by the relation,

$$\tan h(\alpha_n x),$$

where α_n is a positive integer/non-integer constant, n corresponds to the nth CCCCCII and x represents a normalized voltage as the signal input;

weighing circuitry comprised of current mirrors operable with each said CCCCCII output to form a weighted output for each said programmable output;

for each CCCCCII, a corresponding current gain amplifier connected to the output terminal thereof, outputs of the amplifiers being connected together to form summation circuitry which provides an algebraic sum of the CCCCCII outputs, the algebraic sum being characterized by the relation,

$$y(x) = \sum_{n=1}^N \gamma_n \tanh(\alpha_n x),$$

where current $y(x)$ represents the required nonlinear function, α_n is a positive integer/non-integer constant that can be programmed via the bias terminal, and γ_n is a positive/negative integer/non-integer weighting factor as determined by the weighing circuitry.

8. The programmable CMOS-based nonlinear function synthesizer according to claim 7, wherein the common reference potential is ground potential.

9. The programmable CMOS-based nonlinear function synthesizer according to claim 7, further comprising fixed transistor aspect ratios of the weighing circuitry based on the γ_n weighing factors, the fixed transistor aspect ratios not affecting the programmability of the programmable CMOS-based nonlinear function synthesizer.

10. The programmable CMOS-based nonlinear function synthesizer according to claim 9, wherein the fixed transistor aspect ratios (W/L) are approximately 50 $\mu\text{m}/3 \mu\text{m}$.
